UNITED STATES PATENT OFFICE.

FERDINAND BLANC, OF CHARLOTTENBURG, GERMANY, ASSIGNOR TO SIEMENS-SCHUCKERTWERKE, G. M. B. H., OF BERLIN, GERMANY, A CORPORATION OF GERMANY.

INDUCTION-MOTOR.

1,224,895.

Specification of Letters Patent.

Patented May 8, 1917.

Application filed January 16, 1914. Serial No. 812,460.

To all whom it may concern:

Be it known that I, FERDINAND BLANC, a German citizen, and resident of Charlottenburg, near Berlin, Germany, have invented 5 certain new and useful Improvements in Induction-Motors, of which the following is a specification.

My invention relates to induction motors, preferably of polyphase construction, 10 having a short-circuited or squirrel-cage armature which is so constructed that the speed-torque characteristics of such a motor can be modified in order to meet particular service conditions especially those required 15 for driving spinning machinery.

In general spinning machines are repeatedly started or stopped on one and the same day, and the individual spinning machines behave very different in practice as regards 20 the requirement of starting torque. In order to secure the proper working conditions, in every case the start of the machinery must be made very smooth. In starting, one and the same spinning machine will sometimes behave in quite a different way, viz: it will start more sluggish in the morning when it is set in operation than during the course of the day after it has been running one or several times. Also 25 during summer time or in case for other reasons the room temperature is relatively high, the machines will start easier than during winter or at low temperature. It is therefore desirable to be able to start the 30 electric driving motors for the spinning machines with a torque which is adjustable within certain limits. For three-phase induction motors, as ordinarily employed in the present case, an adjustment of the starting torque of the motor upon the temporary load or the mechanical resistance of the spinning machine at starting is only made possible by regulating the short-circuit currents.

In order to obtain a smooth starting with 45 an induction motor having a short-circuited armature for driving spinning machines, an idle armature has been provided on either side of the working armature separately therefrom, which has the purpose to decrease the magnetic flux passing into the rotor by deflecting the flux generated in the stator. For regulating the flux passing through the working armature, and varying the starting torque the idle armatures 55 are made adjustable to be either in direct

magnetic contact with the armature or in a greater or smaller distance therefrom.

The primary object of my present invention is to obtain in a simple and more perfect manner a smooth starting of the motor 60 by having the ordinarily employed short-circuit rings of the squirrel-cage winding of the armature surrounded by magnetizable bodies either permanently or only temporarily during the starting. The decrease 65 of the starting torque in this case is due to the phase-displacement to which the rotor currents are subject in generating a new field independently from the stator field in the magnetizable ring. Another known construction consists therein that the short-circuit rings, the iron surrounding the same and two further rings form transformers proper whereby the reverse effect, that is a high starting torque, is obtained. This latter construction of course is not related to 70 my present invention.

My invention will be more fully understood by reference to the accompanying drawing which shows in longitudinal sections four modes of carrying my invention into effect. In brief Figure 1 shows a construction having a magnetizable ring fixed upon the rotor with slots which is moved to and from the armature according to the 80 working conditions of the motor. Fig. 2 shows a similar construction by which said magnetizable ring is moved by means of a centrifugal device, Fig. 3 a construction in which said ring of magnetizable material 90 is fixed with respect to the bearing of the motor, and Fig. 4 a construction similar to that of Fig. 3 having an additional circular groove on said ring by means of which said ring may be adjusted by an adjusting 95 device such as a lever, spindle or the like.

Referring now more particularly to the drawing *a* is the stator, and *b* the rotor of my motor, and *c* is the axle of said rotor *b*. In Fig. 1 a magnetizable ring *f* is fixed upon 100 the rotor. This magnetizable ring is provided with slots *g* through which conductors *e* lead to the rings *d*. Another magnetizable ring *h* is mounted upon the axle *c* in a manner to be adjustable within certain 105 limits in axial direction, the adjustment being secured by means of a key-way *i* which positively limits the motion. A helical spring *j* is provided between the body of the rotor and the magnetizable ring *h* tend- 110

ing to move the latter away from the former.

If the motor is either at rest or working at normal speed of rotation, the ring *h* is kept away from the ring *f* by means of the spring *j* and will be pressed against the collar *k*. If the motor is started the ring *h* by the magnetic action caused by the current pulsating in the ring *d* will be attracted and compress the spring *j* and come into a position as indicated in Fig. 1, namely surrounding ring-like the short-circuit ring *d* and forming with the fixed ring *f* a good magnetic circuit. In this position of the ring *h* the self-induction in the short-circuit ring *d* will be a maximum and accordingly the starting torque of the motor will reach the desired minimum value. The more the motor is accelerating the more the currents in the short-circuit ring *d* will be weakened, so that the spring *j* can again gradually press the ring *h* backward and if the motor has reached its full speed of rotation the ring *h* also is abutting against the collar *k*.

Such adjustable ring *h* can be provided at both ends of the motor armature for either short-circuit ring thereof; also the rings *h* may be so arranged that they are not positively moving with the motor; furthermore they may be constantly kept fixed in any intermediate position, in order to obtain the proper starting characteristics for any individual machine which is driven from the motor.

The two rings *f* and *h* are advantageously subdivided by a number of radial cuts, or they may be composed of a number of segments which are insulated from each other. In the construction of Fig. 2 the ring *h* is positioned during the standstill of the motor at a minimum distance from the armature, and will be drawn away therefrom by the centrifugal force exerted by the weights *l* of the centrifugal device against the action of a spring *m* to an extent as the motor is accelerating. These weights may be pivotally connected with the one end of guide-bars *o*, the other ends of which are pivoted to the ring *p* mounted fixedly upon the axle *c* and to the hub of the movable ring *h*. Screws *q* or similar devices may serve to adjust the ring *h* to the proper initial position in order to adapt the starting torque to an individual case, as desired.

In Fig. 3 the ring *h* is mounted upon a sleeve *s* of the bearing and does therefore not participate in the rotation of the motor. In this construction the magnetizable ring *f* is substituted by the laminated iron of the rotor *b* and its disks. The operation of this construction will be the same as that of the construction shown in Fig. 1.

In another construction shown in Fig. 4 the ring *h* is also kept in a fixed position

and mounted upon a sleeve of the bearing. For adjusting the ring *h* a circular groove *t* is provided around the hub or central part of said ring. A ring-shaped body *u* fits into the groove *t*, said ring body being made adjustable in axial direction by means of the lever *v* which is pivoted at *w* and connected to said ring *u* by means of the pin *x* which may slide relatively to said lever in a slot *y* thereof. This lever *b* now may be adjusted as desired to bring the magnetizable ring *h* into any position with regard to the armature of the motor, that is to say, in a shorter or greater distance therefrom, to meet the particular load-characteristics of the driven machinery. I have also shown a locking device for locking the lever *v* in a desired position, said locking device being represented in the drawing by the circular rack *z* having its center at *w*, upon which by means of the pawl *10* and the thumb lever *11* the lever *v* may be fixed in any desired position. The ring *h* may also be made adjustable by a number of other constructions, for instance it may be made to rotate upon the bearing sleeve in a thread of any desired gradient, so that by rotating the ring the desired distance between the same and the rotor may be adjusted.

In the constructions of Figs. 3 and 4 the armature conductors are positioned in deep slots of the armature which do not contain any electrically or magnetically active material. In case of rotors according to this construction the adjustable ring *h* serves only for the fine adjustment of the starting torque. The rings *f* in the construction according to Figs. 1 and 2 may also be omitted and screws or similar means for adjustment may also be employed in the constructions of Figs. 1, 2 and 4.

Having thus described my invention I claim as new and desire to secure by Letters Patent of the United States:—

1. In an induction motor of polyphase construction the combination of an armature having a squirrel-cage winding, the electrical resistance of said winding being such as to give a strong starting torque, and means, comprising a movable magnetizable ring partially surrounding a short-circuit ring of said winding, for increasing only the reactance of said winding.

2. In an induction motor of polyphase construction the combination of an armature having a squirrel-cage winding, the electrical resistance of said winding being such as to give a strong starting torque, and means, comprising a movable magnetizable ring divided into a plurality of segments individually surrounding a short-circuit ring of said winding, for increasing only the reactance of said winding.

3. In an induction motor of polyphase construction the combination of an armature

- having a squirrel-cage winding, the electrical resistance of said winding being such as to give a strong starting torque, means comprising a movable magnetizable ring partially surrounding a short-circuit ring of said winding, for increasing only the reactance of said winding, and means for enlarging the distance between said short-circuit ring and said magnetizable ring with increasing speed of said motor.
4. In an induction motor of polyphase construction the combination of an armature having a squirrel-cage winding, the electrical resistance of said winding being such as to give a strong starting torque, means comprising a movable magnetizable ring divided into a plurality of segments individually surrounding a short-circuit ring of said winding, for increasing only the reactance of said winding, and means for enlarging the distance between said short-circuit ring and said magnetizable ring with increasing speed of said motor.
5. In an induction motor of polyphase construction the combination of an armature having a squirrel-cage winding, the electrical resistance of said winding being such as to give a strong starting torque, means comprising a movable magnetizable ring partially surrounding a short-circuit ring of
- said winding, for increasing only the reactance of said winding, and a spring being under tension at the starting period, said spring being adapted to enlarge the distance between said short-circuit ring and said magnetizable ring with increasing speed of said motor.
6. In an induction motor of polyphase construction the combination of an armature having a squirrel-cage winding, the electrical resistance of said winding being such as to give a strong starting torque, means comprising a movable magnetizable ring divided into a plurality of segments individually surrounding a short-circuit ring of said winding, for increasing only the reactance of said winding, and a spring being under tension at the starting period, said spring being adapted to enlarge the distance between said short-circuit ring and said magnetizable ring with increasing speed of said motor.

In witness whereof I have hereunto set my signature in the presence of two subscribing witnesses.
